CLAIM

The ornamental design for a display device, as shown and described.

DESCRIPTION

FIG. 1 is a perspective view of a display device, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines that are immediately adjacent to the claim represent the bounds of the claim, while all other broken lines are directed to environment; the broken lines form no part of the claimed design.

1 Claim, 7 Drawing Sheets
